LUDWIG SCHÖN, OF ESSEN-ON-THE-RUHR, GERMANY, ASSIGNOR TO FRIED. KRUPP AKTIENGESELLSCHAFT, OF ESSEN-ON-THE-RUHR, GERMANY.

ARRANGEMENT FOR EXCITATION OF CONTINUOUS-CURRENT GENERATORS.

1,190,680.

Specification of Letters Patent. Patented July 11, 1916.

Application filed January 7, 1914. Serial No. 810,852.

To all whom it may concern:

Be it known that I, LUDWIG SCHÖN, residing at Essen-on-the-Ruhr, Germany, a subject of the Emperor of Germany, have 5 invented a certain new and useful Improvement in Arrangements for Excitation of Continuous-Current Generators, of which the following is a specification.

The present invention relates to arrangements for excitation of continuous current generators particularly intended for controlling dynamos with Leonard-driving, the exciting current of which is to be furnished by an external source of constant voltage 15 connected in opposition to the armature of said generator. The subject matter of the present invention is an arrangement of this kind, by which the maximum voltage of the armature of the generator, which is to be 20 excited, is made independent of the height of the available external voltage.

In the accompanying drawing one embodiment of this invention is diagrammatically illustrated.

25 A denotes a continuous current generator, the excitation of which is to be changed by the regulation of the current strength in the main field winding D. The rotor C of a continuous current motor is, by 30 means of the conductor B, connected with the armature brushes a^1 and a^2 of the generator A, the field winding C¹ of said motor being separately excited in well known manner. The negative armature brush a^1 of 35 the generator A is connected with one end h^1 of a regulating resistance H, by means of a conductor F¹, and the positive brush a^2 of the generator A is connected with the other end h^2 of the resistance by means of a 40 conductor F. The negative pole of a constant external voltage source G is moreover connected to the point h^1 , and the positive pole of the same source G connected with a point h^3 situated between the ends h^1 45 and h^2 of the regulating resistance H. The main field winding D is on the one hand connected with an auxiliary brush a^3 of the generator armature, and on the other hand with the sliding contact E of the resistance 50 H. The auxiliary brush a^3 , resting on a slip-ring a^4 connected to one point of the winding of the generator armature serves the purpose to divide the armature voltage in the manner of the well known Sengel

connection, so that there is active in the 55 circuits a^2 , F, H, E, D, a^3 or a^3 , D, E, h^1 , F¹, a^1 only a fraction, practically one half, of the armature voltage.

As long as the contact E remains on a point situated between the points h^1 and h^3 60 of the regulating resistance H, the described arrangement operates like the known arrangements for exciting a continuous current generator by means of a constant external voltage source connected in opposition to the generator armature and producing a constant voltage at the brushes a^1 and a^2 . The only difference is, that the value of the voltage opposed to the portion of the external voltage which is determined 70 by the position of the sliding contact E, is only half of the armature voltage. Therefore, the strength of the exciting current running through the circuit G, E, D, a^3 , a^1 , F¹, G depends on the difference of the 75 external voltage and the half armature voltage.

When the contact E is situated in point h^3 , half of the value of the armature voltage is equal to the external voltage less 80 the voltage drop in the winding D, or, in other words, the voltage between the brushes a^1 and a^2 is smaller than the external voltage. Should, however, the contact E be moved in the direction of the arrow α past 85 the point h^3 , the generator will then behave as a self-exciting dynamo, and it will self excite to a greater degree, the more the contact E is moved toward the end h^2 of the resistance H. The exciting current now 90 mainly runs through the circuit a^2 , F, h^2 , H, E, D, a^3 . When, finally, the contact E reaches the point h^2 , the generator A is wholly self excited. Evidently, with the arrangement described, the armature voltage 95 may considerably exceed the amount governed by the contact position h^3 .

Claims.

1. An arrangement for exciting continuous current generators having two main 100 brushes and an auxiliary brush for dividing the voltage of the main brushes, an external source of constant voltage, a regulating resistance connected with two of said brushes, a portion of said resistance serving to connect the armature in opposition to said external voltage source, a sliding contact for said resistance and a main field winding con- 105

nected on the one hand with the third one of said brushes and on the other hand with said sliding contact.

2. An arrangement for exciting continuous current generators having two main brushes and an auxiliary brush for dividing the voltage of the main brushes, an external source of constant voltage, a regulating resistance connected with the two main 10 brushes, a portion of said resistance serving to connect the armature in opposition to said external voltage source, a sliding contact for

said resistance and a main field winding connected on the one hand with said auxiliary brush and on the other hand with said 15 sliding contact.

The foregoing specification signed at Barmen, Germany, this 17th day of December, 1913.
